US0D1048654S

(12) United States Design Patent (10) Patent No.: US D1,048,654 S
(45) Date of Patent: * Oct. 29, 2024

(54) GARMENT

(71) Applicant: LULULEMON ATHLETICA CANADA INC., Vancouver (CA)

(72) Inventor: Lok Lam Yeung, Vancouver (CA)

(73) Assignee: LULULEMON ATHLETICA CANADA INC., Vancouver (CA)

() Term: 15 Years

(21) Appl. No.: 29/834,453

(22) Filed: Apr. 12, 2022

(51) LOC (14) Cl. 02-02

(52) U.S. Cl.

USPC D2/840

(58) Field of Classification Search

USPC D2/840, 717, 731, 749

CPC A41D 1/04

See application file for complete search history.

(57) CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view thereof shown in an environment of use; and, FIG. 8 is a rear view thereof shown in an environment of use.

The portions of the garment shown in broken lines in FIGS. 1-8 do not form part of the claimed design. The broken line showing of the arms, torso, neck, and head in FIGS. 7-8 is for the purpose of illustrating portions of the environmental structure and forms no part of the claimed design.

1 Claim, 8 Drawing Sheets
